UNITED STATES PATENT OFFICE.

PAUL MAUSER, OF OBERNDORF-ON-THE-NECKAR, GERMANY.

AUTOMATIC FIREARM.

1,091,857.

Specification of Letters Patent. Patented Mar. 31, 1914.

Application filed December 26, 1912. Serial No. 738,664.

To all whom it may concern:

Be it known that I, PAUL MAUSER, royal privy commercial councilor, subject of the King of Wurttemberg, at Oberndorf-on-the-Neckar, in the Kingdom of Wurttemberg, German Empire, have invented certain new and useful Improvements in and Relating to Automatic Firearms, of which the following is a specification.

10 The invention relates to a recoil loader of the kind described in the specifications of Patents Nos. 943,949 and 971,061 its object being the special arrangement of the locking means covered by these patents which has 15 proved to be suitable and advantageous in view of the peculiarity of the weapon as a self-loading pistol with breech carriage guided on the grip.

The essence of this invention resides in the 20 fact that the two retaining members which are mounted at the front end of the grip co-operate with a lower projection from the block which moves between them, the adjusting slide for moving the retaining members 25 inward and outward being arranged beneath same and engaging inwardly directed projections thereon. To facilitate adjustment by hand, a separate member is also provided which engages with the slide 30 and is rockably mounted directly in the trigger guard so that when the weapon is grasped it can be readily seized with one finger.

An embodiment of the invention is illustrated in the accompanying drawing, in which:

Figure 1 is an elevation of the weapon closed and cocked partly in section. Fig. 2 is a horizontal longitudinal section of the 40 front portion of the grip. Fig. 3 is an elevation corresponding to Fig. 1, showing the breech block in its rearward position. Fig. 4 is a section corresponding to Fig. 2 showing the parts in the position that they occupy in Fig. 3. Fig. 5 is a longitudinal section corresponding to Fig. 1. Fig. 6 is an elevation of the breech closure. Figs. 7 and 8 show the slide in elevation and plan view, respectively. Figs. 9 and 10 are an elevation and a plan view, respectively, of a supporting flap.

In the extension g^1 of the grip g which engages beneath the barrel in the known manner a slide s is longitudinally displaceable and is pressed rearward by a spring s^2 (Fig. 5). Two retaining members b are

mounted in the grip extension g^1 beside this slide; they are rotatable about pins b^1 and by means of projections b^2 engage in corresponding recesses s^1 in the slide s . These members b are controlled by the slide s in such a manner that in the rear position of this slide (Fig. 2) their front ends are directed inward and support a projection v^1 of the breech block v from behind, thereby locking the breech block in closing position. In this position they are held by the spring s^2 of the slide s . On firing, the slide s effects a relative forward movement owing to its inertia in opposition to the action of its spring, the supporting members b being turned outward so that the projection v^1 of the breech block is able to move backward between them. In order to effect by hand this unlocking of the breech block which takes place automatically on firing a member k is rotatably mounted in the trigger guard and engages by means of a rib k^1 in a corresponding recess s^3 in the slide. By pressing on the front face of this pressure member the slide s is pressed forward, whereby the retaining members b are set in the open position.

The mounting of the slide and of the retaining members in the forward extension 85 of the grip and the arrangement in the trigger guard of the member co-operating with the slide is particularly advantageous for pistols because it renders it possible to unlock the breech readily and conveniently in the grip position.

What I claim as my invention and desire to secure by patent is:

1. In a recoil operating pistol, the combination of a frame comprising a grip, a breech-block, locking-levers for said breech-block, and a recoil operated slide for actuating said locking-levers, said locking levers and said slide being located in the forward part of said frame in front of said grip. 100

2. In a recoil operated pistol, the combination of a frame comprising a grip, a breech-block, locking-levers for said breech-block located in the forward part of said frame in front of said grip, a projection on the front end of said breech-block extending between said locking levers and adapted to be engaged by said locking levers to lock said breech-block, and a recoil operated slide for actuating said locking-levers. 105

3. In a recoil operated firearm, the combination of a breech-block, locking-levers for

2
said breech-block, a recoil operated slide for actuating said locking-levers, a spring acting upon said slide to cause the same to move said locking-levers to locking position, and means adapted to be manually operated for moving said slide against the pressure of said spring to move said locking-levers to unlocking position.

4. In a recoil operated firearm, the combination of a breech-block, locking levers for said breech-block, a recoil operated slide for actuating said locking-levers, a spring acting upon said slide to cause the same to move said locking-levers to locking position, and a pivoted lever adapted to be manually operated for moving said slide against the pressure of said spring, to move said locking levers to unlocking position.

5. In a recoil-operated pistol, the combination of a frame comprising a grip, a breech-block, locking-levers for said breech-block, a recoil-operated slide for actuating said locking-levers, a spring acting upon said slide to cause the same to move said locking-levers to locking position, means adjacent said grip and adapted to be operated by a finger of a user when the firearm is held by the grip, said means operating to move said slide against the pressure of said spring to move said locking levers to unlocking position.

6. In a recoil-operated pistol, the combination of a frame comprising a grip, a

breech-block, locking-levers for said breech-block, a recoil operated slide for actuating said locking-levers, a spring acting upon said slide to cause the same to move said locking-levers to locking-position, and a pivoted lever adjacent said grip and adapted to be conveniently operated by a finger of a user when the firearm is held by the grip, said lever operating to move said slide against the pressure of said spring to move said locking-levers to unlocking position.

7. In a recoil-operated pistol, the combination of a frame comprising a grip, a breech-block, locking-levers for said breech-block, a recoil-operated slide for actuating said locking-levers, said locking-levers and said slide being located in the forward part of said frame in front of said grip, a spring acting upon said slide to cause the same to move said locking-levers to locking position, and means adjacent said grip and adapted to be conveniently operated by a finger of a user when the firearm is held by the grip, said means operating to move said slide against the pressure of said spring to move said locking levers to unlocking position.

In testimony whereof I have affixed my signature in presence of two witnesses.

PAUL MAUSER.
